APPARATUS FOR THE LIQUID TREATMENT
OF YARNS AND THE LIKEHorace P. Fry, Jr., Swarthmore, Pa., assignor to
American Viscose Corporation, Wilmington,
Del., a corporation of Delaware

Application February 6, 1948, Serial No. 6,693

7 Claims. (Cl. 68—205)

1

This invention relates to the treatment of yarns, tows, or other strands of natural or artificially produced fibers or filaments with liquids and is particularly concerned with the treatment of such yarns with liquids as they are advanced through a path comprising a plurality of laterally spaced convolutions.

In accordance with the present invention, one or more treating liquids are applied to a strand of the filamentary material to be treated as it passes through a path comprising a plurality of laterally spaced convolutions, such as those of a helix, and after the liquid has exerted its effect upon the strand, it is largely removed from the zone of treatment by stripper means having an arcuate edge disposed in a plane transverse of the axis of the convolutions and closely adjacent the rotor but out of contact with the convolutions thereof. Such stripper means may serve to remove one or more treating liquids from the lower rotor of a pair about which the convolutions are carried or from the lower periphery of a thread-advancing reel about which the yarn follows a helical path for discharging the liquid into one or more collecting means, such as troughs, the liquids being kept separate wherever desired by the use of a separate stripper means and separate collecting container or trough. In certain instances, the stripper may be provided beneath the upper of a pair of canted rotors and be provided with a conduit discharging the liquids stripped from the upper rotor on to a predetermined portion of the lower of the pair of rotors. When a plurality of liquids are applied to such a pair of rotors, a plurality of stripper means may be provided with the upper rotor for keeping the several liquids applied separate and for separately applying the liquids stripped from the upper rotor to predetermined zones of the lower rotor.

In the drawing, which is illustrative of the invention,

Figure 1 is a side elevation, with parts in cross-section, of one embodiment of the invention,

Figure 2 is an end elevation of the embodiment shown in Figure 1,

Figure 3 is a side elevation of a modification,

Figure 4 is an end elevation of the embodiment of Figure 3,

Figure 5 is a perspective view of the stripper provided between the rotors of Figures 3 and 4,

Figure 6 is a perspective view of the stripper associated with the lower rotor of Figures 3 and 4 and cut on line VI—VI of Figure 3,

Figure 7 is a side elevation of a modification, and

2

Figure 8 is an end elevation of the modification of Figure 7.

Referring now to Figures 1 and 2, a thread-advancing reel shown generally at 3 and comprising interdigitating bars 4 and 5 between which relative motion is imparted in any conventional fashion, such as shown in Patents 2,403,031 and 2,404,005, is mounted on an inclined axis as by means of the bearing 6 and is driven through the shaft 7 and the gear 8 secured thereto.

Collecting means is provided beneath the reel and comprises a container or trough 9 which, when separation between several liquids is desired, may be partitioned as by the plates 10 and 11 respectively. The several troughs may be provided with outlets 12 for draining the liquids from the troughs, and for connection through suitable conduits to recovery or replenishing means. Liquids may be supplied by means of conduits 13 provided with any suitable outlets 14 for applying the liquids to the convolutions of thread upon the reel. The outlets 14 may be in the form of a nozzle, spray head, or the like.

As shown, three different liquids are applied to different zones of the reel and because of the inclination of the reel between the horizontal and the vertical, preferably at a small angle of about 2 to 5° from the horizontal, the liquids tend to flow down to the lower end of the reel as they flow around the circumference thereof. Adjacent the lower end of each zone of treatment, stripper means is provided which in the figures are shown as baffles or plates 15, 16 and 17 respectively. These strippers have an arcuate edge at 18 (see Figure 2) which is closely adjacent to the rotor comprising the bars 4 and 5 of the reel but out of contact with the convolutions of yarn carried thereabout, so that as the liquid gathers or accumulates toward the lower end of the zone it projects from the bars and the convolutions into contact with the arcuate edge 18 which strips it from the rotor and conveys the liquid into the collecting means. As shown in Figure 1, the stripper may take several forms. Thus that shown at 15 is disposed in a vertical plane and is adjustable in height by virtue of the cap screws 15a extending through slots 15b in the lower portion of the stripper plate 15. That at 16 is also adjustable in height but is disposed at a somewhat different angle than 15. Although both strippers 15 and 16 lie in planes extending transversely of the axis of the reel, the plane of stripper 16 is substantially at right angles to the axis of the reel, whereas that of 15 is somewhat inclined to this because of the inclined disposition

40

of the reel relative to the vertical plane of the baffle. The stripper 17 is connected by a bracket or arm 18 to one wall of the trough 9 to which it may be adjustably clamped as at 19. Like the plate 16, the plane of stripper 17 is at right angles to the axis of the rotor.

By advancing the convolutions of yarn in the helix from the lower end to the upper end of the reel, countercurrent flow may be obtained in this manner and the several liquids may be effectively stripped and maintained separate in their several zones by application to the convolutions.

In the embodiment of Figures 3 to 6, the convolutions of thread proceed about two canted rotors 20 and 21, both of which are inclined at a small angle to the horizontal and to each other so that the liquid may be applied to the outer upper end and flow back toward the inner lower end along each of the rotors. When the convolutions proceed from the inner or supported ends of the rotors toward the outer ends thereof, counterflow can be obtained.

The rotors may be supported on shafts 22 mounted rotatably in a suitable framework or support 23 and provided with gears 24 by which either or both may be driven. Liquid may be supplied to the upper of the two rotors by a conduit 25 terminating in a discharge outlet, such as a nozzle or spray head 26. Stripper means may be provided toward the lower end of the lower rotor for removing the liquid therefrom and comprises an arcuate stripper plate 27 disposed in a plane extending transversely of the axis of the rotor. This stripper 27 has an arcuate edge in close proximity to the rotor but out of contact with the convolutions of yarn thereon so that gathered or accumulated masses of liquid projecting outwardly from the convolutions will make contact with the stripper. An additional stripper 28 extending longitudinally of the rotor and having an edge 29 in close proximity to the rotor but out of contact with the convolutions of yarn thereon, may be provided to remove accumulated or gathered liquid along a portion of or along the entire length of the rotor. As shown in Figure 6, the stripper 28 may constitute a central or intermediate rib projecting upwardly from the bottom of a trough 30 which, as shown, may gradually widen from the outer end to the inner end where it is supported by the frame 23. The stripper 27 may be supported at one end of the stripper 29. The bottom of the trough slopes downwardly and terminates in an outlet 32 which serves to discharge the liquid into a trough 33 which may run transversely of the rotor axes the length of a machine comprising a plurality of such canted rotor units.

Between the upper and lower rotors, there may optionally be provided a stripper 34 which is of arcuate construction as shown in Figure 5 and discharges into a trough 35 supported by a bracket 36 extending from the frame 23 which serves as a conduit to direct the liquid stripped by the stripper 34 from the inner end of rotor 20 to any predetermined portion, such as the outer end of rotor 21. The bottom of trough 35 slopes downwardly toward the unsupported end of the rotors and terminates in a perforated bottom 37. If desired, a longitudinal stripper 38 may be provided for removing some of the liquid gathered at the bottom of the upper rotor at points extending a considerable distance out from the stripper 34. The stripper 34 has an arcuate edge in close proximity to the rotor but out of contact with

the convolutions of yarn similar to the stripper 27. The arcuate edge of stripper 34 and the upper edge of stripper 38 may in fact be so closely adjacent to the rotor 20 as to actually make contact therewith as long as there is no contact with the turns of yarn. When these strippers are positioned in contact with the rotor, they may advantageously be formed of a flexible or elastic material such as rubber or synthetic rubber to give a good squeegeeing contact with the rotor surface. However, it extends about the stripper 27 in order to avoid interference with the courses of the yarn extending between the two rotors.

In this embodiment, liquid adhering to the bottom of the upper rotor is displaced toward an upper portion of the lower rotor and this removal from the upper rotor together with the flowing of a portion of the liquid down the two generally parallel sheets of yarns extending between rotors serves to transfer the partially spent liquid collecting on the upper rotor to the lower rotor so that there is less dilution of the fresh liquid supplied to the upper rotor by spent liquid thereon.

Figures 7 and 8 show a modification comprising two rotors, canted with respect to each other as in the embodiment of Figures 3 and 4, about which the yarn is progressed in a series of laterally displaced convolutions from the inner supported ends to the upper unsupported ends of the rotors. The rotors may be driven as in Figures 3 to 4 and are supplied with liquids through conduits 40 terminating in discharge outlets 41. As shown four different liquids are applied to axially spaced zones of the rotors and stripper means 42 are provided below the lower rotor toward the ends of the treatment zones adjacent the lower end of the rotor. As in previous embodiments, the strippers have arcuate edges closely adjacent the rotor but out of contact with the turns of yarn thereabout. The strippers are associated with separate collecting means 43 such as the partitioned compartments of a trough carried on a bracket 44. This partitioned trough may extend the length of the machine beneath a plurality of pairs of canted rotors so that each individual trough formed by the partitions serves to collect liquid from a plurality of thread-treating units.

Between the rotors, there may optionally be provided strippers 45 spaced at those ends of the treating zone which are adjacent the lower end of the upper rotor. As in Figures 3 to 6, the strippers 45 may make direct contact with the lower surface of the upper rotor and longitudinal strippers 46 may be provided adjacent the strippers 45. The collecting means comprising the conduits 47 may be provided to convey the liquid stripped from certain of the zones to troughs 48 extending transversely of a group of units and longitudinally of a machine comprising such a group. The construction in this case is similar to the troughs 30 and 33 of Figures 3 to 6. As shown, liquid is removed from one of the zones maintained separate and so discharged. In the outer two zones, the liquid collected is directed through the conduits 49 which terminate in perforated heads 50 above predetermined zones of the lower rotor. The conduits 49 and stripper means associated therewith may be supported by a common bracket or post 51 secured to the frame 52 of the machine. As shown, the discharge outlets 50 are disposed toward the upper ends of the respective zones upon the lower rotor. If desired,

the liquids stripped from all of the zones of the upper rotor may be directed to corresponding zones of the lower rotor. Alternatively, the liquids stripped from the several zones of the upper rotor may be withdrawn entirely from the system as is done with the two liquids applied to the zones at the lower end of the upper rotor in Figures 7 and 8.

It is to be understood that changes and variations may be made without departing from the spirit and scope of the present invention as defined in the appended claims.

I claim:

1. Apparatus for treating yarns with liquids comprising two rotors mounted, one at a higher level than the other, on axes inclined to the horizontal and vertical for advancing a yarn and the like through a path comprising a plurality of laterally spaced convolutions extending about the rotors, the axes of the rotors being inclined to one another, means for rotating the rotors about their respective axes, means adjacent the upper rotor for applying liquids to the convolutions thereon in a treatment zone of the path, stripper means below the upper of said rotors and between it and the lower of said rotors comprising an arcuate edge in a plane transverse of the rotor axis at the end of the treatment zone toward the lower end of the rotor, said edge being closely adjacent to the rotor but out of contact with the convolutions of yarn upon said upper rotor, and conduit means connected to the stripper means to receive liquid therefrom and having a discharge opening adjacent the lower rotor for directing such liquid to the lower rotor, whereby liquid gathering about the yarn convolutions at the bottom of the upper rotor is stripped therefrom and directed to the lower rotor.

2. The apparatus of claim 1 in which the said rollers are inclined to the horizontal in the same general direction and in which the discharge opening from the said conduit means is spaced axially from the arcuate edge toward the upper end of the lower of said rotors.

3. Apparatus in accordance with claim 1 comprising means below the lower of said rotors for collecting the liquid, and stripper means below said lower rotor and between it and the collecting means comprising an arcuate edge in a plane transverse of the lower rotor axis at the end of the treatment zone toward the lower end of the lower rotor, said edge being closely adjacent to but out of contact with the convolutions of yarn upon the lower rotor, whereby liquid gathering at the bottom of the lower rotor is stripped therefrom and discharged into the collecting means.

4. Apparatus in accordance with claim 1 in which the said rollers are inclined to the horizontal in the same general direction, and in which additional means for applying liquids to additional axially spaced zones of the convolutions and corresponding stripper means are provided with their arcuate edges adjacent the upper rotor at the lower ends of the respective zones, and their respective discharge openings are spaced axially from their arcuate edges toward the upper end of the lower rotor.

5. Apparatus in accordance with claim 1 in which the stripper means comprises an edge extending longitudinally of the rotor.

6. Apparatus for treating yarns with liquids comprising a rotor mounted on an axis inclined to the horizontal and vertical for advancing yarn and the like through a path comprising a plurality of laterally spaced convolutions extending about the rotor, means for rotating the rotor about its axis, means adjacent the rotor for applying liquid to the convolutions in a treatment zone of the path, a container spaced below the rotor for collecting the liquid away from the rotor, drainage means associated with the container to prevent the liquid collected therein from contacting the rotor, and stripper means below said rotor and between it and the container comprising a plate having the bottom of both of its faces free to discharge to the container and having an arcuate edge in a plane transverse of the rotor at the end of the treatment zone toward the lower end of the rotor, said edge being closely adjacent to but out of contact with the convolutions of yarns upon the rotor, whereby liquid gathering about the yarn convolutions at the bottom of the rotor is stripped therefrom, discharged into the container away from the rotor and drained therefrom.

7. Apparatus for treating yarns with liquids comprising two rotors mounted, one at a higher level than the other, on axes inclined to the horizontal and vertical for advancing a yarn and the like through a path comprising a plurality of laterally spaced convolutions extending about the rotors, the axes of the rotors being inclined to one another, means for rotating the rotors about their respective axes, means above the rotors for applying liquid to the convolutions in a treatment zone of the path, a container spaced below the lower of said rotors for collecting the liquid away from the rotors, drainage means associated with the container to prevent the liquid collected therein from contacting the said lower rotor, and stripper means below said lower rotor and between it and the container comprising a plate having the bottom of its faces free to discharge to the container and having an arcuate edge in a plane transverse of the lower rotor axis at the end of the treatment zone toward the lower end of the lower rotor, said edge being closely adjacent to but out of contact with the convolutions of yarn upon the lower rotor, whereby liquid gathering about the yarn convolutions at the bottom of the lower rotor is stripped therefrom, discharged into the container away from the rotor and drained therefrom.
